UNITED STATES PATENT OFFICE

JOHN W. FOYLE, OF KANSAS CITY, MISSOURI, ASSIGNOR TO GUSTIN-BACON MANUFACTURING CO., OF KANSAS CITY, MISSOURI, A CORPORATION OF MISSOURI

BRAKE RIGGING

Application filed May 31, 1928. Serial No. 281,692.

My invention relates, more particularly, to brake-rigging for railway cars involving mechanism by which the slack between the brake-mechanism and the actuating element therefor, as for example and more particularly, a manually operable element, may be quickly taken up and thereafter sufficient power exerted by the actuating element to produce a degree of pressure of the brake shoes against the wheels necessary and desirable to effect proper setting of the brakes.

One of my objects is to provide a novel, simple, inexpensive and positively operating mechanism for accomplishing the purposes stated which may be incorporated in brake-rigging operated manually only, or brake-rigging operated selectively, either by power, as for example compressed air, or manually.

Another object is to provide against such accumulation of ice or rust on the mechanism by which the quick take-up of the slack is effected and the desired leverage for setting the brake-actuating element is exerted, as will prevent, or impair, the proper functioning of the mechanism, and other objects as will be manifest from the following description.

Referring to the accompanying drawings:

Figure 1 is a plan view of certain portions of an air brake mechanism of a well known form showing my improvement incorporated therewith, the underframe of the car, one end only being shown, being represented by dotted lines.

Figure 2 is a view in side elevation of the structure shown in Fig. 1.

Figure 3 is a view in side elevation of the mechanism by which the slack is taken up and the desired leverage exerted against the brake-actuating element, the clip for supporting the mechanism being shown in section.

Figure 4 is a plan view of the structure shown in Fig. 3.

Figure 5 is a longitudinal section taken at the irregular line 5-5 on Fig. 4 and viewed in the direction of the arrows.

Figure 6 is a section taken at the line 6

on Fig. 5 and viewed in the direction of the arrow; and

Figure 7, a section taken at the line 7 on Fig. 5 and viewed in the direction of the arrow.

I have illustrated my invention as embodied in compressed air operated brake rigging, of a well known construction, and involving a compressed-air-operated cylinder 10 mounted on the underframe 11 of the car and containing a piston (not shown) rigidly connected with the push rod 12 connected with an arrangement of levers and rods whereby the movement of the push rod 12 in one direction sets the brakes and its movement in the opposite direction releases them.

One of the levers of the arrangement referred to is represented at 13 it being pivotally connected at a pin 14 with the outer end of the push rod 12 and also pivotally connected at 15 and 16 with rods 17 and 18, respectively, the rod 17 connecting with the brakes at one end of the car and the rod 18 to the mechanism for setting the brakes at the other end of the car, it being understood that when the lever 13 rocks in counterclockwise direction in Fig. 1 and the push rod 12 moves to the right in this figure the brakes will be set.

The arrangement shown comprises a vertical brake staff 19 rotatably supported at an end of the car and equipped at its upper end, in accordance with common practice, with a manually operable element (not shown), as for example a hand wheel.

Interposed between the air-operated mechanism above described and the brake-staff 19 is my improved mechanism which, in accordance with the preferred illustrated embodiment of my invention comprises a sheave 20 rotatably mounted on a journaling pin 21, shown as a bolt, with a tube 21^a forming a roller interposed therebetween, the pin 21 being secured in the vertical side portions 22 of a yoke 23 one side portion of which is shown as provided with a horizontal plate extension 24 underlying, and rigidly secured to, the center sill 25 of the car underframe 11. Extending around the sheave 20 is a flexible element, shown as a chain 26, attached at

one end to the sheave, as through the medium of a bolt 27 carried by the sheave and extending through the terminal link of the chain, the other end of this chain being rigidly connected with the brake staff 19, as represented at 28, the arrangement of the parts just described being such that when the brake-staff is rotated in clockwise direction in Fig. 1 the chain will be wound upon the brake-staff and 10 unwound from the sheave 20 thereby rotating the latter in clockwise direction in Figs. 2, 3 and 5.

The hub portion 29 of the sheave 20 is provided at opposite sides with segmental pinions 31 and 32 concentric with the shaft 21, the sheave 20 being provided substantially coincident with the bottom of the groove 33 in the periphery of the sheave 20, with axially aligned projections 34 and 35 which project from opposite faces of the sheave.

Cooperating with the sheave wheel 20 is a member 36 shown as in the form of a hollow frame casting containing in its opposite frame sides 37 longitudinally extending slots 38 into which the ends of the tube 21^a extend, this frame being adapted for lengthwise movement in a direction crosswise of the shaft 21.

The opposite end of the member 36 is 30 adapted for connection and support by the compressed-air-operated mechanism of the brake rigging, the connection shown being at the pivoting pin 14 which extends through the vertically spaced arms 36^a at this end of 35 the member 36. The opposed frame sides 37, on their inner surfaces, are provided with downwardly opening pockets 40 and 41, respectively, each presenting spaced wall portions 42 and 43. These pockets are formed 40 in upwardly projecting extensions 44 and 45 of the frame sides 37 and are so positioned as shown that when the braking mechanism 45 is out of operative position and the member 36 occupies the position shown in the drawings, the pockets 40 and 41 are positioned in advance of the shaft 21, the lower portions of the walls 42 of the pockets being curved as represented at 46, for the purpose herein-after stated.

50 The side members 37 of the frame 36 are provided with rack portions 47 and 48 extending longitudinally of these members.

The projections 34 and 35 are adapted for 55 cooperation with the pocket portions, respectively, of the member 36 and the segmental pinions for cooperation with the racks 47 and 48.

The operation of the mechanism is as follows: Assuming that the parts of the mechanism are in the position shown in the drawings, in which position the brakes controlled thereby are released, rotation of the brake-staff 19 in clockwise direction in Fig. 1 rotates the sheave 20 and consequently the projections 34 and 35 and mutilated pinions 31 and

32 in clockwise direction in Figs. 2, 3 and 5.

In this normal, brake-released, position of the parts, the projections 34 and 35 extend part way into the pockets 40 and 41, respectively, and therefore when the staff 19 is rotated as stated, the member 36 is shifted to the right in Figs. 1 to 5, inclusive, thereby actuating the brake rigging connected therewith to take up the slack therein. As the projections 34 and 35 move out of the pockets 40 and 41, in the continued rotation of the brake-staff 19 and the sheave 20, the mutilated gears 31 and 32 move into mesh with the racks 47 and 48, respectively, so that the remainder of the movement of the member 36 and the brake rigging connected therewith, is effected through this pinion drive, in which operation the brakes are moved to set condition.

Inasmuch as the projections 34 and 35 are positioned radially outwardly from the shaft 21 a greater distance than the teeth on the segmental pinions 31 and 32, the engagement of the projections 34 and 35 with the member 36 being in effect a crank engagement, the member 36 and the brake rigging parts connected therewith are actuated from the brake-staff 19 initially at a greater speed and with the exertion of less leverage than during their operation by the engagement of the pinions 31 and 32 with the racks 47 and 48. Thus the operator in manually operating the brake-staff 19 may quickly take up the slack which exists in the brake rigging and the take-up of which does not require much power, and immediately thereafter, by the engagement of the pinions with the racks, apply the pressure necessary to properly set the brakes.

It is necessary in a construction of this character to provide against any possible locking of the mechanism in the shifting 105 from low leverage application of power to the member 36 to high leverage application, and vice versa, and this is accomplished in the present construction by driving the member 36 with low leverage application of power 110 thereto for taking up the slack, by means of the mechanism described operating as a crank and relieving the surfaces as above described and indicated at 46.

In this connection it will be noted that 115 the pinions engage the racks just before the projections 34 and 35 move out of the pockets and as the speed of rotation of the sheave 20 accelerates upon the engagement of the pinions with the racks, the projections referred to move out of the pockets without fouling.

It will be noted that the member 36 is supported at one end by the compressed-air-operated mechanism and therefore avoids 125 the necessity of providing means solely for the support of the member 36 at this end thereof, as would be necessary were the connection between the member 36 and the brake rigging such as not to provide a support for this member.

It will also be noted that the member 36 and the sheave 20, by being directly connected with the compressed-air-actuated brake rigging, are operated each time the 5 brakes are set by the application of air pressure. This is desirable as the frequent relative movements of these parts and the chain about the sheave, prevent such accumulations of ice or rust as would render the 10 operation of the hand-operated mechanism difficult, if not impossible.

It will be understood that the principle of 15 operation underlying the illustrated embodiment of my invention may be carried out in a mechanism in which the crank drive and the pinion drive of the member 36 is effected by single elements, as distinguished from the pairs of projections 34 and 35 and pinions 31 and 32, these parts being provided 20 in pairs and arranged as shown inasmuch as thereby the forces applied in the operation of the mechanism are substantially balanced and this is preferred as the structure may thereby be made lighter and without danger 25 of impairment of the operating parts.

While I have illustrated and described a 30 particular construction embodying my invention, I do not wish to be understood as intending to limit it thereto, as the same may be variously modified and altered without departing from the spirit of my invention.

What I claim as new, and desire to secure 35 by Letters Patent, is:

1. In combination, an operating element, 40 a shiftable member, a rotatable member having a fixed axis of rotation, means actuated by said element for rotating said rotatable member, and means actuated by said rotatable member for actuating said shiftable 45 member comprising a crank-device driven by said rotatable member and operatively engaging said shiftable member in the initial rotation of said rotatable member for moving said shiftable member at a relatively great speed and means operated in the 50 continued rotation of said rotatable member and exerting increased leverage against said shiftable member and moving the latter at a relatively slow speed.

2. In combination, an operating element, 55 a shiftable member, a rotatable member having a fixed axis of rotation, means actuated by said element for rotating said rotatable member, and means actuated by said rotatable member for actuating said shiftable 60 member comprising a crank-device driven by said rotatable member and operatively engaging said shiftable member in the initial rotation of said rotatable member for moving said shiftable member at a relatively great speed and rack and pinion mechanism operated in the continued rotation of said rotatable member and exerting increased leverage against said shiftable member and 65 moving the latter at a relatively slow speed.

3. In combination, an operating element, 70 a shiftable member, a rotatable member having a fixed axis of rotation, means actuated by said element for rotating said rotatable member and comprising a flexible element wound upon the periphery of said rotatable member, means actuated by said rotatable member for actuating said shiftable member comprising a crank driven by said rotatable member and operatively engaging said shiftable member in the initial rotation of said 75 rotatable member, and means operated in the continued rotation of said rotatable member and exerting increased leverage against said shiftable member and moving the latter at a relatively slow speed, said crank engaging said shiftable member closely adjacent the portion of said rotatable member against which said flexible element bears and operating to move said shiftable member at 80 a relatively great speed.

JOHN W. FOYLE.
